UNITED STATES PATENT OFFICE.

HARVEY P. MCFARLAND, OF OQUAWKA, ILLINOIS, ASSIGNOR OF ONE-HALF TO
CHARLES W. BALDRIDGE, OF CHICAGO, ILLINOIS.

RAIL ANCHOR.

Application filed May 11, 1922. Serial No. 560,027.

To all whom it may concern:

Be it known that I, HARVEY P. MCFARLAND, a citizen of the United States, residing at Oquawka, in the county of Henderson, 5 State of Illinois, have invented certain new and useful Improvements in Rail Anchors; and I do hereby declare the following to be a full, clear, and exact description of the invention, such as will enable others skilled in the art to which it appertains to make and use the same.

This invention relates to a rail anchor for a railroad rail and is of the type adapted to be clamped to the rail and having a part 15 contacting with a cross tie to prevent longitudinal or creeping movement of the rail.

It is an object of this invention to provide such an anchor comprising few parts and which can be quickly attached to and 20 detached from the rail.

It is another object of the invention to provide a rail anchor comprising an integral member adapted to extend under the rail and having portions adapted to overlap the flange thereof at both edges, said member being arranged to receive a single 25 clamping member.

These and other objects and advantages of the invention will fully appear from the 30 following description taken in connection with the accompanying drawings, in which like reference characters refer to the same parts throughout the different views and, in which,

35 Fig. 1 is a view in front elevation of the device showing the same loosely applied to a rail, a portion of the device being shown in section;

Fig. 2 is a plan view of the device showing a rail and cross tie and showing the clamping pin in section;

Fig. 3 is an end view of the device showing a rail and cross tie; and

Fig. 4 is a view in elevation of the clamp- 45 ing pin.

Referring to the drawings:-

A rail of usual cross section is indicated at *b* having the flange portion *c* adapted to contact with the cross tie *d*.

50 The rail clamp comprises an integral member having a portion *1* adapted to extend beneath the flange *c* of the rail in contact therewith, which portion is shown as having the central strengthening rib *1^a* ex- 55 tending longitudinally of its bottom sur-

face. Said member also has an upstanding portion at one end provided with a lip *2* adapted to overhang one edge of the rail flange and has also an upstanding portion at its other end having a lip *3* of somewhat greater extent than the lip *2* also adapted to overhang the edge of the rail flange. The lip *3* and the portion *1* have aligned substantially vertical holes *4* extending therethrough, and a transverse rib *5* having a comparatively sharp edge projecting into the recess between the lip *3* and the portion *1*.

The shape of the holes *4* is shown in Fig. 2, the same having a flat side adjacent the rail with parallel sides extending therefrom connected by a semi-circular curve.

The member *1* is provided adjacent one end with a depending portion *7* having an outer flat surface and a central rib extending under the portion *1*.

A pin *6* is provided and adapted to be disposed in the holes *4* having a supporting collar *6^a* at one end adapted to rest on the lip *3* and an angular shaped head *6^b* for turning the same.

This pin is shown as having a cylindrical shank flattened on one side so as to provide unequal lengths of its opposite diameters, but the pin can be made oblong in shape in cross section if desired.

In operation the clamp will be applied to the rail flange with the pin *6* removed. The distance between the inner edges of the lips *2* and *3* is sufficient for the passage of the rail and the clamp can be swung unto the rail as indicated by the dotted line position of the rail in Fig. 1. After the rail flange is fitted under the lips *2* and *3*, the device is moved to the right as seen in Fig. 1 and the pin *6* is then inserted through the holes *4*, the short diameter of the pin extending transversely of the rail. When the pin is now turned by a suitable wrench the long diameter thereof will then be turned transversely of the rail and the sides of the pin will bear against the edge of the rail flange and the edge of the rib *5*. This movement of the pin will thus draw the clamp firmly against the opposite edge of the flange and the device will be firmly clamped to the rail.

When it is desired to remove the clamp, the pin *6* need only be turned to bring its short diameter extending transversely of the rail when it can be removed.

and the clamp also removed. When the clamp is in place, the plane surface of the side 7 will be placed in contact with the cross-tie *d* and the clamp will thus effectively prevent any longitudinal movement or creeping of the rail relatively to the cross-tie.

From the above description, it is seen that applicant has provided a very simple and efficient form of clamp and one that can be easily and inexpensively made. The clamp can be very quickly placed in position and just as quickly removed. As stated, the shank of pin 6 can be made of various shapes in cross section just so diameters of different lengths are provided. Means can also be provided if desired for holding the pin 6 in its clamping position.

It will, of course, be understood that various changes may be made in the form, details and proportions of the parts without departing from the scope of applicant's invention, which generally stated consists in the matter shown and described and set forth in the appended claims.

What is claimed is:—

1. A rail anchor comprising a member having a portion adapted to extend transversely beneath a rail and having upstanding portions at each end provided with lips overhanging the top of the rail flange, one of said lips and said first mentioned portion having aligned substantially vertical holes therethrough and a member extending through said holes having a section opposite the rail flange of unequal diameters, whereby the same can be turned to wedge against the rail and said member and clamp the latter in position.

2. A rail anchor comprising a member adapted to extend transversely beneath the rail having an extended lip at one end overhanging the edge of the rail flange and having a lip at its other end, spaced from

its main portion and adapted to overhang the top of the rail flange, said last mentioned lip and said member having substantially vertical aligned holes therethrough, a clamping member adapted to extend through said holes, and a transverse rib having a comparatively sharp edge extending transversely of said first mentioned member between said last mentioned lip and the main body portion of said member and between said holes.

3. A two piece rail anchor comprising a member adapted to extend beneath the rail and having an extending lip at each end thereof adapted to extend over the edges of the rail flange, said member having a downwardly extending portion adjacent one end having a flat surface adapted to contact the cross tie and having aligned holes through one end portion and one of said lips and a member disposed in said holes, adapted when turned, to cam against the rail flange.

4. A rail anchor comprising a member having a portion adapted to extend transversely beneath the rail and a downwardly extending portion at one end having a flat surface adapted to contact a cross tie, said member also having an upwardly extending portion at each end from each of which a lip projects adapted to overhang the top of the rail flange, said member having a hole therethrough at one end and a hole through one of said lips aligned therewith and a clamping pin disposed in said holes supported upon said lip and having its end of angular formation and a shank having a portion disposed opposite the edge of a rail flange of unequal diameters, operative when turned to cam against the rail and clamp the same in position.

In testimony whereof I affix my signature.

HARVEY P. McFARLAND.
